PUMP

James P. Sullivan, Hobbs, N. Mex., assignor of
fifty-one per cent to Mary B. Weir, Hobbs,
N. Mex.

Application March 30, 1939, Serial No. 265,055

1 Claim. (Cl. 103—156)

This invention appertains to new and useful improvements in pumps of the submerged type.

The principal object of the present invention is to provide a pump especially adapted for deep well submerged use.

Another important object of the invention is to provide a pump wherein the plunger with its packing means can be readily removed from the pump without disconnecting the pump from the tube line.

These and other important objects and advantages of the invention will become apparent to the reader of the following specification.

In the drawings:

15 Figure 1 represents a side elevational view of the pump.

Figure 2 is a longitudinal sectional view through the pump.

Figure 3 is a cross sectional view.

20 Figure 4 is a side elevational view of the working barrel and flange.

Figure 5 is a bottom plan view of the shell top.

Figure 6 is a top plan view of the bottom of the shell.

25 Figure 7 is a top plan view of the socket screw.

Figure 8 is a section on the line 8—8 of Figure 2.

Referring to the drawings wherein like numerals designate like parts, it can be seen that numeral 4 represents the cylindrical shell which has the sleeve 5 extending upwardly from its upper end and internally threaded to receive the lower end of the reducer 6 which, in turn, is connected to the lower end of the pipe line 7.

35 At the lower end of the shell is the apron 8 threadedly engaged at its upper end into the lower end of the sleeve 9 which extends downwardly from the lower end of the shell 4. Interposed between the upper end of the apron 8 and the lower end of the shell 4 is the bottom wall 10 having a pair of threaded openings 11—12 therein into which are threadedly engaged the short tubular cages 13 and 14 to accommodate the ball valves 15 and 16, respectively. Each of

45 these tubes 13 and 14 has openings 17 therein and at its upper end a stop pin 18 to prevent displacement of the corresponding balls 15 or 16. The top side of this wall 10 has the diametrically disposed groove 19 therein for receiving the lower portion 20 of the partition 21. This partition 21 is in the form of a flange extending laterally from the working barrel 22 and downwardly below its lower end. As is clearly shown in Figure 3, the shell 4 is divided into the sections a—b 50 and the edge portions of the flange 21 extending

from each side of the working barrel 22 is disposed between the opposed edges of the sections a—b and these edges of both the shell sections and the partition flange 21 are welded together as at 23. Thus two chambers, namely 24 and 25 5 are defined in the shell 4.

The top wall 26 for the shell 4 has its bottom side formed with the diametrically disposed grooves 27 for receiving the upper edges of the partition flange 21 and is further formed with 10 openings 28 to receive the check valve shells 26' for the chamber 24 and the check valve shells or cages 27' for the chamber 25. These check valves are constructed the same as the check valves 13 and 14. The upper end portion of the 15 working barrel 22 extends upwardly through the opening 28 in the top 26 and is internally tapered to receive the tapered plug 29 which contains the packing filled pocket 30 and the screw 31 20 operative against the same. The screw is tubular for slidably receiving the plunger rod 32 which has the plunger 33 at its lower end made up of a plurality of packing elements for snug wiping engagement against the inner side of the working barrel 22. The packing compression screw 31 has 25 the head 34 which as shown in Figure 7 has the square socket 35 therein for receiving the square block 36 on the rod 32 when the rod is lowered sufficiently to engage the block 36 in the socket 35. When this engagement is made the rod 32 30 can be rotated with the result that the packing screw 31 is rotated and the packing 30 compressed to the desired extent.

When it is desired to remove the plunger and the foregoing packing means without disturbing 35 the tube line 7, the plunger 33 can be moved upwardly and by pounding against the plug 29 the entire plug in its packing gland can be dislodged from the working barrel 22 and elevated through the tube line 7.

40 In the operation of the pump it can be seen that on the down stroke (see Figure 2) water moves upwardly through the skirt 8 and through the check valve 14 to the chamber 25 and flows into the working barrel 22 through the opening 45 37, as water in the working barrel 22 below the plunger 33 is forced out through the openings 38 and upwardly through the chamber 24 to the tube line 7 by way of the check valves 26'. Reverse action takes place when the plunger is moved in 50 an upward direction.

While the foregoing specification sets forth the invention in specific terms, it is to be understood that numerous changes in the shape, size and materials may be resorted to without departing 55

from the spirit and scope of the invention as claimed hereinafter.

Having described the invention, what is claimed as new is:

- 5   In a pump of the character described, a shell, a bottom plate in the shell having valved ports and a groove therein, a top plate in the shell having an aperture and a groove and valved ports therein, a working barrel in said shell having an upper end extending through the aperture in said top plate, a partition in said shell extending diametrically from opposite sides of said barrel and below the lower end thereof, said partition
- 10

having top and bottom ends mounted in the grooves of the top and bottom plates, respectively, and dividing the shell into a pair of compartments, a packing gland in the upper end of said working barrel, a plunger in said working barrel, 5 and a rod connected to said plunger and extending through said gland, said barrel being provided with apertures in the upper and lower ends thereof the apertures in the upper end communicating with one of said chambers and the apertures in the lower end communicating with the other of said chambers.

JAMES P. SULLIVAN.
